GRILL MOUNTING

Lawrence S. Riendeau, Springfield, Mass., assignor to Westinghouse Electric & Manufacturing Company, East Pittsburgh, Pa., a corporation of Pennsylvania

Application September 26, 1939, Serial No. 296,538

4 Claims. (Cl. 312—1)

My invention relates to a cabinet having a grill extending across an air inlet or outlet opening, more particularly to means for mounting the grill in the cabinet, and it has for an object to provide an improved structure of the character set forth.

Another object is to provide a grill mounting means having a minimum portion thereof disposed exteriorly of the cabinet, so as to provide a pleasing appearance.

A further object is to provide means whereby the grill may be quickly and easily mounted and removed.

These and other objects are effected by my invention as will be apparent from the following description and claims taken in connection with the accompanying drawings forming a part of this application, in which:

Fig. 1 is a vertical section taken on the line I—I of Fig. 2;

Fig. 2 is a front elevation, with a part in section taken along the line II—II of Fig. 1; and,

Fig. 3 is a perspective view.

Referring to the drawings in detail, I show my invention incorporated in a cabinet 10 which encloses a fan motor unit 11, the latter comprising a fan 12 and a motor 13 for driving the fan. The complete article including the cabinet and the fan motor unit is known as a cabinet fan. It is adapted to be placed on the floor, a table, or any other suitable supporting surface. The fan motor unit is removably and pivotally mounted on the side walls of the cabinet, as disclosed and claimed in the application of Gustav H. Koch, Serial No. 295,924, filed September 21, 1939 so that it may be tilted to direct air in an upwardly-inclined direction when the cabinet fan is placed on the floor.

The body portion of the cabinet is preferably made of wood, as shown on the drawings, and comprises side walls 14 and 15, a bottom wall 16, corner portions 17 and 18 extending between the side walls, and top and rear wall portions 19 and 20 extending between the side walls. The cabinet is formed with an inlet opening 21 in the back and an outlet opening 22 extending across the front and also the front portion of the top of the cabinet, so that air may be discharged either horizontally or in an upwardly-inclined direction.

The cabinet is provided with inlet and outlet grills 23 and 24 extending across the inlet and outlet openings, respectively. These grills may be of any suitable form; in the illustrated embodiment, they comprise vertically extending

spaced parallel wires 25 and cross wires 26 to which the ends of the wires 25 are secured in any suitable manner, as by soldering. As will be noted from the drawings, the grills 23 and 24 are formed so that the portions thereof extending across the openings are disposed substantially flush with the outer surfaces of the cabinet. They are, however, formed with marginal portions which extend beyond the edges of the openings and are bent inwardly and disposed against the inner sides of the adjacent wall portions of the cabinet, which are beveled to suitably fit said marginal portions, as will be clear from Fig. 1.

The wall portion 19 is formed with a groove 27 in which the upper cross wire 26 of the outer grill is disposed. Two clamp members 28, detachably fastened to the wall portion 17 by screws 29, bear against the cross wire 26 to retain the same in the groove 27.

The wall portion 17 is recessed as shown in Fig. 1 to receive the lower cross wire 26, which is secured by clamp members 28 similarly to the upper cross wire. The outlet grill 24 is mounted or removed while the inlet grill 23 is removed, during which time access to the fastening means comprising the clamp members 28 and the screws 29 may be had through the inlet opening 21.

The rear wall portion 20 is formed with a groove 31 for receiving the upper cross wire of the inlet grill 23. Two spring clips 32 are secured to the wall portion 20 by screws 33 and are adapted to resiliently engage the upper cross wire and retain the same in the groove 31. These clips project downwardly below the lower edge of the rear wall portion 20. The cross wire is positioned by engaging the lower ends of the clips 32 on the outer side and moving the cross wire upwardly between the clip and the beveled surface of the wall portion 20 until it enters the groove 31.

The wall portion 18 is also formed with a recess for receiving the lower cross wire 26 of the inlet grill 23. This cross wire is held in the recess by two clamping members 34, secured by screws 35 which extend through the wall portion 18 and are screw-threaded through the clamp members 34. The screws 35 have heads 36 which are substantially flush with the outer surface of the cabinet and which are formed with kerfs where the screws may be turned to tighten the clamp members 34. The clamp members 34 are of the form shown in Fig. 2 so that when the screws 35 are loosened they may be turned at right angles to disengage the cross wire 26 without being separated from the screws.

To remove the inlet grill 23, the screws 35 are first loosened and the clamp members 34 turned to the horizontal position shown in dotted lines in Fig. 2. The lower end of the grill is then swung inwardly and the upper end of the grill is pulled downwardly from between the clips 32 and the rear wall portion 20. The grill may then readily be removed, the upper end being removed first.

To replace the grill, the lower end of the grill is first inserted through the inlet opening and moved toward the interior thereof to permit the upper end to be moved between the spring clips 32 and the beveled surface of the wall portion 20 until the upper cross wire 26 engages in the groove 31. The lower end is then swung into place against the wall portion 18, whereupon the clamp members 34 are turned to vertical position and the screws 35 tightened by means of a screw driver engaging the kerf in the heads on the exterior of the cabinet.

From the above description and from the drawings, it will be seen that I have provided novel means for mounting a grill in a cabinet in a manner to provide a pleasing appearance, since most of the parts are disposed interiorly of the cabinet, and whereby the grill may be quickly installed or removed.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. A cabinet having an opening therein for flow of air between the interior and the exterior of the cabinet, a grill extending across said opening and formed so that the main portion thereof is substantially flush with the outer surface of the cabinet, opposite marginal portions of said grill being bent inwardly and extending on the inner side of wall portions of the cabinet adjacent the opening, one of said wall portions being formed with a groove for receiving the edge of one of said marginal portions and being provided with spring clips for retaining the same therein, clamp members adapted to engage the edge of the other marginal portion and to retain the same against the inner side of the adjacent wall portion, and screws extending through said clamps and the adjacent wall portion and having kerf heads in the outer face of said wall portion

55

whereby the same may be turned to tighten the clamp members.

2. A cabinet having an opening therein for flow of air between the interior and the exterior of the cabinet, a grill extending across said opening and comprising spaced wires extending between opposite wall portions of the cabinet with the ends thereof underlying said wall portions, a clamp member disposed on the inner side of one of said wall portions for holding the adjacent marginal portion of said grill against said inner side of said wall portion, and a screw extending through said clamp member and said wall portion and having a kerf head on the outer side of said wall portion, said wires being spaced sufficiently so that said clamp member may be manipulated by extending one's fingers between said wires.

3. A cabinet having an opening therein for flow of air between the interior and the exterior of the cabinet, a grill extending across said opening, opposite marginal portions of said grill being bent inwardly and extending on the inner side of wall portions of the cabinet adjacent the opening, one of said wall portions being formed with a groove for receiving the edge of one of said marginal portions and being provided with spring clips for retaining the same therein, clamp members adapted to engage the other marginal portion and to retain the same against the inner side of the adjacent wall portion, and screws extending through said clamp members and the adjacent wall portion and having kerf heads in the outer face of said wall portion whereby the same may be turned to tighten the clamp members.

4. A cabinet having an opening therein for flow of air between the interior and the exterior of the cabinet, a grill extending across said opening and formed so that the main portion thereof is substantially flush with the outer surface of the cabinet, opposite marginal portions of said grill being bent inwardly and extending on the inner side of wall portions of the cabinet adjacent the opening, one of said wall portions having means to retain the adjacent marginal portion upon movement of the latter in a direction from one to the other of said wall portions, clamp members adapted to engage the other marginal portion and to retain the same against the inner side of the adjacent wall portion, and screws extending through said clamp members and the adjacent wall portion and having kerf heads in the outer face of said wall portion whereby the same may be turned to tighten the clamp members.

LAWRENCE S. RIENDEAU.
